DESIGN FOR A SUPPORTING BELT

Julius J. Goldstein, New York, N. Y.

Application July 5, 1947, Serial No. 140,112

Term of patent 7 years

(Cl. D3—10)

To all whom it may concern:

Be it known that I, Julius J. Goldstein, a citizen of the United States, resident of the city of New York, county and State of New York, have invented a new, original, and ornamental Design for a Supporting Belt, of which the following is a specification, reference being had to the accompanying drawing, forming part thereof.

In the drawing, the figure is a perspective view of a supporting belt, showing my new design.

I claim:

The ornamental design for a supporting belt, substantially as shown.

JULIUS J. GOLDSTEIN.
